COMBINED ARCH AND SOLE FOOTPAD

Mary Frances Lee, Brooklyn, N. Y.

Application September 25, 1945, Serial No. 618,506

1 Claim. (Cl. 36—71)

1

This invention relates to new and useful improvements in a combined arch and sole protector for the interior of a shoe.

More specifically, the present invention proposes the construction of a pad adapted to be inserted in a shoe and being characterized by having an air-containing flexible member covered by special materials best suited for their intended purposes as will present appear.

It is desired to provide a pad which will help to build an individual's instep and protect and build the arch according to the shape of his foot. The pad provides an inside platform so that the foot can be raised, to prevent it from being subject to shock and other abuse due to hard floors and concrete and to cushion it from the friction between the foot and the shoe. The pad is designed to protect the complete sole of the foot to the arch so as to give relief from callouses, burning feet and other foot injuries resulting from misfitted shoes. By maintaining the feet in their own natural shape and form by using the pad, in due time the feet will lose all the soreness which has been caused by the use of various types of hard metals and hard rubbers, such as are used in other types of pads. As the pad is placed from the ball of the foot down to the longitudinal arch, the foot is raised to give it enough support and feeling of a complete arch and metatarsal pad, and releases also any pressure on the heel of the foot.

The characteristics of the pad of the present invention that enable it to aid the feet are that the pad is only a quarter of an inch or a half-inch thick, soft, flexible and that it fits into the shoe without moving back and forth. Because of its delicate substance, it treats the feet in such a sensitive way that there is a chance while walking to relax and heal or mend previous aches and pains, and to replace fatty tissue worn away through the constant friction between the foot and footwear over a period of years of hard walking, etc.

All other attempts made before in pads have been treating each part of the foot separately with various parts of metal or hard sponge rubber and have not given complete relief to the entire foot, but only to parts and at times they have even broken down the muscles of some other part of the foot. This pad gives comfort to the complete sole of the foot from the ball of the foot down to the longitudinal arch. As the arch is raised in height one quarter or one-half of an inch, and the foot is bedded in a soft cushion, the muscles are held in control and the various

2

parts that have been broken down have a chance to rebuild themselves without any discomfort. At the same time, any pressure on the heel of the foot is released.

Some treat the foot by adding side pieces of sponge rubber and others by raising the metatarsal or arch wherever the foot gives one trouble. The "airstep pad" takes care of the complete foot and doesn't allow one's feet to become disfigured. A further advantage is that it gives one correct posture because it enables one to walk erect. It can be worn in high heeled shoes to its best advantage, as well as in low heeled shoes.

Walking on hard surfaces breaks down the bone structure of the foot as well as wearing down important foot tissues. As our shoes are made so that the foot does not stay in one place, our feet are hurt by the friction of hard walking, especially in women's high heeled shoes, with their thin soles. The tiniest nerves are irritated when the foot moves back and forth. The pad of the present invention is fitted into the shoe so well that it keeps the foot in perfect balance to prevent it from slipping back and forth, and has it resting on a cushion which prevents these friction burns and relieves all discomforts.

The airstep pad of the present invention fits comfortably in men's shoes as well as women's shoes, and no change in the construction of the pad is necessary when it is to be used as such.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a pad constructed in accordance with this invention.

Fig. 2 is a sectional view taken on the line 2—2 of Fig. 1.

Fig. 3 is an inverted plan view of a portion of the pad.

Fig. 4 is an inverted plan view of a pad constructed in accordance with a modification of this invention.

Fig. 5 is a cross section through a pad constructed in accordance with a further modification of this invention.

Fig. 6 is a cross section through a pad constructed in accordance with a further modification of this invention.

The pad or platform shown in Figs. 1-3, according to this invention, comprises a bottom:

layer of suede leather 10, this layer being soft and flexible and being shaped to closely fit in the shoe for which it is constructed with the side margins of the layer turning up slightly along the sides of the shoe to get a firm grip therealong so that the layer will frictionally hold the pad against sliding.

A layer of coarse mesh cloth 11 is superposed and cemented on top of the layer 10. Then comes another layer of coarse mesh cloth 12, free from the mesh 11 but secured by the adhesive to a layer of fine mesh cloth 13. A layer of silk or rayon 14, which may be waterproofed, is secured by the adhesive to the upper surface of the layer 13.

A smaller pad of sponge rubber 15, of the same general shape as the leather 10, has cemented to its lower surface a layer of fine mesh cloth 16 which has been rubberized with the cement. The air rubber is covered with a layer of waterproofed silk or rayon 17 which is secured to the air rubber with an adhesive. This layer 17 is folded under the air rubber and overlaps the lower surface of the layer 16 to which it is sewed by stitches 18. The pad thus has two members, the top member consisting of the air rubber 15, and the layers 16 and 17 and the bottom or platform member or base consisting of the remaining layers. These remaining layers are sewed together by stitches 19. The two members are secured together with the adhesive.

In the embodiment of the invention shown in Fig. 4 the pad is similar to the pad of Figs. 1-3 except that the suede leather layer 10^a is formed of two parts abutting at 20 which is curved transversely of the layer 10^a. This structure adds flexibility to the layer 10^a.

Another pad constructed in accordance with a further modification of this invention is shown in cross section in Fig. 5. It has the same external shape as the pad of Fig. 1. However, it has two layers of suede leather 10^b and 21 sewed together by stitches 22 around their margins. The top member of this pad includes air rubber 15^b, a layer of cheesecloth 23 and thereon a layer of rubberized silk or rayon 17^b, both layers 23 and 17^b being folded under the edge of the rubber pad the bottom of the rubber pad and the margins of the layers 23 and 17^b being covered by a layer of cheesecloth 16^b, which is sewed to these margins. Layers 16^b and 23 are cemented to the rubber pad and the top member is cemented to the top of the suede leather layer 21.

Another pad constructed in accordance with a further modification of this invention is shown in Fig. 6. It distinguishes from the pad of Fig. 5 in that the two suede leather layers 10^c and 21^c are cemented together, eliminating the stitches 22. Other parts corresponding to similar parts of the pad of Fig. 5 are indicated by like references with the letter c suffixed. It is to be understood that while certain materials have been mentioned as forming a part of the construction of this invention, any suitable material such as plastics, etc. may be used if so desired.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention what I claim as new, and desire to secure by United States Letters Patent is:

An arch and sole protector for insertion in a shoe having a top section shaped to conform to the shape of the inside of the shoe at the shank thereof, a laminated bottom section secured to the bottom face of the top section, said laminated bottom section having edge portions projected beyond the edges of the top section, whereby the projected edge portions at the sides of the bottom section will extend upwards along the inner side walls of the shoe holding the protector in position, the bottom layer of said laminated bottom section comprising a sheet of suede leather for frictionally gripping the inside surfaces of the shoe, said bottom suede layer being formed of separate parts abutting one another along a transverse arcuate line so as to render the protector flexible for bending along its length.

MARY FRANCES LEE.
